UNITED STATES PATENT OFFICE.

JÜRGEN KASSCHAU AND JACOB A. KASSCHAU, OF NEW YORK, N. Y.

DESIGN FOR A LAMP AND CHANDELIER BODY.

SPECIFICATION forming part of Design No. 14,463, dated December 4, 1883.

Application filed October 2, 1883. Term of patent 7 years.

To all whom it may concern:

Be it known that we, JÜRGEN KASSCHAU and JACOB A. KASSCHAU, of the city, county, and State of New York, have invented a new and original Design for Lamp and Chandelier

Bodies, of which the following is a full, clear, and exact description, reference being had to the accompanying drawings, making part of this specification, in which—

10 Figure 1 represents a side elevation of a chandelier with our improved body; and Fig. 2 is a horizontal section on line *x-x*, Fig. 1, on a larger scale.

Similar letters of reference indicate corresponding parts.

The design relates to lamps or chandeliers; and it consists of the design of a lamp or chandelier body of round or polygonal shape, having ornamental panels.

20 A in the drawings represents the body of a gas or petroleum lamp or chandelier, which

body is made of round or polygonal shape. The surface of the body A is covered with small panels B, whereby a very rich and artistic appearance is imparted to the lamps or chandeliers.

Having thus described our invention, we claim as new and desire to secure by Letters Patent—

The design for the body of a lamp or chandelier, consisting of a body of round or polygonal shape, having panels, as shown and described.

In testimony that we claim the foregoing as our invention we have signed it this 27th day of September, 1883.

JÜRGEN KASSCHAU,
JACOB A. KASSCHAU.
